CHARACTERISTIC CHANGER

Jerzy J. Wilentchik, New York, N. Y.

Application January 20, 1950, Serial No. 139,572

12 Claims. (Cl. 201—48)

1
This invention relates to improvements in voltage generating systems, wherein it is desired to produce an output voltage "v" as a desired function $v=f(x)$ of angular displacement "x" of a control means.

An object of the invention is to provide a system of the aforementioned character in which the desired voltage function can be set with extreme precision from data presenting the function in a tabular form, by shifting taps along a calibrated scale or by measuring the amount of resistance between successive taps.

In general, any functional voltage-rotation relationship $v=f(x)$ can be simulated accurately by a sufficiently large number of potential points on the curve of the function and by linear interpolating means between respective potential points.

The instrument consists basically of a voltage divider resistance connected across a source of voltage and operating in conjunction with an interpolating potentiometer. Intermittent connections in parallel are made between preselected sectors of the divider and the potentiometer through use of a commutator and of an intermittent-stepping coupling. The sectors are selected by means of taps readily attached to the voltage divider resistance to conform to a desired voltage taper.

Several features of novelty characterize this invention over the existing art.

One of them provides taps adjustable manually along the length of a voltage divider.

Another feature of novelty embodies the principle of combining the individual characteristics of a voltage divider, a commutator and a linear potentiometer into a functionally adjustable voltage generator.

For a better understanding of the invention and the specific objectives attained with its use, reference should be had to the following description and accompanying drawings in which preferred embodiments of the invention have been illustrated and described.

In the drawings:

Fig. 1 is a cross-section according to the invention.

Fig. 1a is a schematic representation of the interpolating components.

Figs. 2, 3 and 4 are detailed views of modification of the attachable contact seen in Fig. 1.

Referring to Fig. 1 the following arrangement of tapped, adjustable voltage divider is being used to impart varying magnitudes of potential to respective bars 2 of commutator 1. A voltage

divider 50 consisting of turns of resistance wire 4 is wound along the length of helical shaped groove 3 in a non-conducting and heat resisting mandrel 5. The extremities of wire 4 are connected by a pair of conductors (not shown) to a voltage source (not shown). The voltage distribution along the length of the resistance wire 4 is uniform assuming uniform threading, uniform wire material and uniform wire distribution in the grooves 3. Thus, the potential at any selected point of wire 4 is a linear function of length and can be identified easily by the number of complete and incomplete turns of said wire contained between a terminal thereof and the selected point. A cylindrical and non-conducting cup 6 encloses the mandrel 5 and is characterized by multiple turns of a spiral continuous slot 7, the latter being narrower than the width of the groove 3 and in alignment with it. A contact pin 9 is retained within a barrel 10 slidably. The upper part 10a of the barrel 10 is a hollow cylinder, the external diameter thereof being slightly less than the width of the slot 7. The lower part 10b of the barrel 10 forms a flange of rectangular cross section with rounded corners, the shorter side of said flange being less than the width of slot 7, the longer side thereof being more than the width of slot 7 and less than the width of groove 3. Thus the flange 10b is adapted to be manually inserted through slot 7 into the groove 3 when its longer side aligns with the length of slot 7 and may be locked therein by a 90 degree turn thereof to either side. A positive electrical contact between the pin 9 and the wire 4 is sustained by the intermediary of spring 8, the latter inserted in the hollow section of the holder 10, and adapted to become compressed between the pin 9 and a conducting plug 11 pressed into the upper section of the cylinder 10b, when the holder 10 is inserted in the slot 7. The cup 6 and the mandrel 5 are held together by screws. The plug 11 is connected by conductor 11a to a respective commutator bar 2.

A design modification of the attachable contact is shown in Figs. 2, 3 and 4 where a contact pin 12 is provided at its middle section with a flange consisting of a pair of wings 12a and 12a' of rectangular cross-section with rounded corners and tapered outside surfaces. The bottom end 50 of the pin 12 is adapted to become conductively associated with the resistance wire 4 when inserted in the slot 7, and may be locked therein by a 90 degree turn to one side, upon which the tapered surfaces of the wings 12a and 12a' cooperate with the inner surface of the cup 6. The

wedge effect thus produced creates the necessary pressure between the point 125 and the wire 4. It should be borne in mind that the wing 12a is tapered conversely to the wing 12a' to facilitate the insertion in the slot 7.

By having "n" complete turns of wire 4 around mandrel 5, "n" being preferably a decimal number, each complete turn assumed to allow "m" different relative positions of the holder 10 with respect to the former, we obtain the total number of such possible positions at $(m)x(n)$, which number represents the accuracy with which the instrument can be set. If $n=10$ and $m=100$ and the input voltage is 100 volts, the resolution or the voltage drop per unit length of the resistance 15 wire would be 0.1 volt, and the highest accuracy of output which could be obtained regardless of other factors would be 0.05%. By inserting the holder 10 in a selected suitable slot 7, and at a suitable radial location along the perimeter thereof, the potential of a respective bar in the commutator 1 can be controlled within 0.01 volt accuracy.

A resistance coil wound helically on a core can be of course used instead of the resistance wire 4. 25 A pair of supports 21 and 21a provide for an adequate elevation of the cup 6 above the ground and enable the insertion of taps 10 in the underneath section of slots 7 in said cup.

The following part of the specification describes 30 the operation of the "interpolating mechanism.

Referring to Figs. 1 and 1a, a sleeve 15 carries the commutator 1 and forms an internal and concentric section of the cup 6. The commutator 1 consists generally of conducting bars 2 inserted 35 circumferentially in the plastic disc 2a, arranged at an equal distance from the center of said disc and at equal distance from each other. It is understood of course, that many other designs of commutator could be used instead of the one proposed in Fig. 1. A pair of similar spring contacts 16 and 17 (only the contact 16 being shown in Fig. 1) are spaced from each other at a distance equal to the center distance of a pair of contiguous bars 2, and are connected by respective 40 conductors 18 and 19 to a pair of terminals 52a and 52b seen in Fig. 1a on an "interpolating resistance" 36. Since the maximum possible displacement of the contacts 16 and 17 is assumed less than one complete revolution the twisting of 45 the conductors 18 and 19, extended through hollow internal section of the sleeve 15 would be negligible in this arrangement. The sleeve 15 may be provided with conveniently located apertures to facilitate the wiring of the conductors 18 and 19. The elements 16 and 17 are attached to a non-conducting contact carrier 26 and are adapted to be displaced by a step intermittent motion in conductive engagement with said bars and along the length of the outside perimeter thereof.

The intermittent motion coupling 28 consists of a pair of coaxial crown gears 22 and 23, the first one of said pair adapted to become rotationally entrained in the displacement of the second one, both mounted loosely on the sleeve 15. The gear 22 is provided with a number of teeth equal to the number of bars 2. The gear 23 may have a number of teeth similar to that of the gear 22, or a lesser number of teeth, provided that said teeth are distributed along the circumference of said gear at such uniform distance from each other as to mesh with respective teeth of the gear 22. A disc 25 having a cam like projection 25a, the latter adapted to cooperate with a guide 24 soldered or otherwise

attached to the sleeve 15 is mounted on the gear 23. The gear 23 is adapted to be axially displaced along the length of sleeve 15 in a direction towards the gear 22 whenever the projection 25a becomes physically engaged with the guide 24. The gears 22 and 23 become locked which results in rotational entrainment of the normally stationary gear 22 during all such times that the gear 23 and the guide 24 are in physical engagement. The shape of the projection 25a and the width of the guide 24 are coordinated to produce upon every complete revolution of the gear 23, or more specifically each time that the gear 23 and the guide 24 become engaged and disengaged, a step motion of the gear 22 and a resulting displacement of respective contacts 16 and 17 by a distance which is equal to the distance between a pair of contiguous bars in the commutator 1. The contact carrier 26 is mounted on the gear 22 and adapted to displace thus the contacts 16 and 17 with regard to respective bars 2. The gear 23 is adapted to be entrained in the rotational displacement of the input member 31, mounted on shaft 15 through transmitting rods 27 attached to disc 31a, the latter being a part of the member 31. The rods 27 extend slidably through closely fitting slots in the gear 23 and are provided with respective springs 29 adapted to return the gear 23 all the way to the right and disengage the gear 22 when the gear 23 becomes separated from the guide 24.

To obtain an accurate centering of the contacts 16 and 17 with regard to their respective bars 2, a locking device 30 can be used. The section of circumference of the sleeve 15, which carries the gear 22 is notched, indented or otherwise artificially roughened to provide for such intermittent frictional resistance that will produce uniform step displacement of said contacts upon each clutching action of the gears 22 and 23 and then lock them in their newly assumed position. The notches 28 are equally spaced along the perimeter of the sleeve 15, relatively to bars 2 and are adapted to cooperate engagingly with locking pointer 32, the latter being carried by the gear 22 and pressed against said notches by spring 33, the magnitude of pressure applied being controlled by adjustable screw 34. Thus 50 the gear 22 is being protected from accidental loose motions; it may assume only few relative positions with respect to the commutator 1 and may become displaced from such once assumed position, only by engagement with the gear 23 which would provide an adequate amount of energy to compress the spring 33 and thus unlock the gear 22. The radial distribution of respective notches 28, their depth and the pressure exerted against them by the pointer 32 may be 55 correlated to produce a step motion of the gear 22 and displace the contacts 16 and 17 from the center of their associated bars to the center of the next following ones. The width of either one of the contacts 16 and 17 is less respectively than the width of respective bars 2, and is less than the width of the insulation layer between the latter, thus the possibility of a short circuit between any pair of such bars is eliminated.

The disc 31a carries a plastic plate 35a, the latter provided with a contact spring 35 being in simultaneous conductive engagement with "interpolating resistance" 36, the turns of the latter arranged toroidally around and along the periphery of a ring form mandrel 36a and 75 with a conducting ring 37. Both the resistance

36 and the ring 37 are inserted concentrically to each other and to the sleeve 15 in respective grooves of a non-conducting holder 38 connected to said sleeve and being therefore stationary. A pair of pointers 40 and 41 may be attached respectively to the link 26 and to the disc 31a for indicating the complete and the fractional revolutions of the member 31 on dial divisions which may be marked on the cup 6. The ring 37 is connected by means of conductor 43 to the output terminal 44 of the instrument. A stop (not shown) may be attached to the sleeve 15 or to any other stationary component of the device and may be adapted to cooperate with a cam (not shown) in the gear 22 to limit the displacement of said gear to less than one complete revolution.

The operation of the interpolating mechanism described above is as follows:

The potentials of a pair of respective contiguous bars 2 are applied to the terminals of the interpolating resistance 36, which should in general be provided with sufficiently large ohmage not to allow an appreciable current flow through it, which could disturb the potential distribution along the selective resistance 4. Assuming that the interpolating resistance has been linearly wound, the potential drop along its length is linear and the output potential would be a linear function of displacement of the input member, such linearity holding for every complete revolution of the input member, said completer revolutions being counted in either direction starting from the "zero position" of the input member. In the "zero position" the contact 35 is situated between the terminals of the interpolating resistance 36. The stepping motion device 20 is adjusted to produce step displacement of the gear 22 whenever the contact 35 crosses the neutral spacing between the terminals of the interpolating resistance. Thus, for complete first, second, third and any following revolutions of the input member, linear interpolations are obtained between the potentials of respective first and second, second and third, third and fourth and etc. bars of the commutator 1 as a function of displacement of the input member 31.

Referring then to Fig. 1a, there are shown schematically the commutator 1, its associated contacts 16 and 17, the interpolating resistance 36 and its associated contact 35, the latter connected to the output terminal 44. The contacts 16, 17 and 35 move in the same direction which may be clockwise or anti-clockwise depending on the sense of displacement of the input member (not shown in Fig. 1a but similar to that seen in Fig. 1). The contact 16 is connected conductively by conductor 51a to terminal 52a of the resistance 36, similarly the contact 17 is connected by conductor 51b to the other terminal thereof 52b. Respective layers of insulation 53 separate contiguous bars 2. The width of the layer 53 is equal to or larger than the width of either one of the contacts 16 and 17, thus eliminating the possibility of a short circuit between any two bars 2. Assuming a clockwise sense of rotation of the input member, the contact 35 would be displaced clockwise from its position along the resistance 36 towards the terminal 52b. The distance separating the contacts 16 and 17 may be made approximately equal to the width of the insulation layer 53. In the normal position shown, the contacts 16 and 17 would be stationary and would cooperate with a pair of

contiguous bars 2a and 2b. When the rotating contact 35 engages the terminal 52b, the gears 22 and 23 of the intermittent motion coupling shown in Fig. 1 become locked and a clockwise entrainment of both elements 16 and 17 results. First the conducting area between the contact 16 and the bar 2a diminishes, and finally the terminal 52b becomes neutralized which corresponds to the contact 16 eclipsing totally the insulation layer 53a. The contact 17 is being displaced concurrently in conductive engagement with the bar 2b towards the insulation 53b and its potential remains thus constant. The fact of the terminal 52a losing its potential does not have an effect on the potential of the contact 35, since the latter assumes the potential of the bar 2b directly from the engaged terminal 52b. Upon further clockwise displacement of the input member, the contact 16 would become conductively united with the bar 2b, the contact 17 would engage on the insulation 53b and the contact 35 would become conductively united with the terminal 52a and maintain thus the output terminal 44 at the potential of the bar 2b. When the contact 17 becomes in turn conductively united with the bar 2c, the terminal 52b assumes the potential of the latter and a linear voltage drop between the potentials of respective bars 2b and 2c is produced along the length of resistance 36. The width of the respective bars 2 depends on the effective conductive area of the contacts 16 and 17; it should be less than the combined length of a pair of such contacts and the insulation layer 53 and more than the length of either one of them separately. It is to be understood that the locking device 30 could be still used with this arrangement, not to produce a step motion of the gear 22 but to lock it in its normal position shown, against accidental motions.

What I claim as novel, and desire to secure by Letters Patent, is:

1. In combination, a mandrel, a groove in said mandrel, a resistance means disposed within said groove, a plurality of contact elements, locking means common to said elements and to said groove to lock said elements at any desired point of said groove in electrical engagement with said resistance means.
2. The combination according to claim 1, wherein said groove is a multi-turn, undercut cavity.
3. The combination according to claim 2, wherein said contact elements are spring loaded.
4. The combination according to claim 3, wherein said contact elements are flanged.
5. The combination according to claim 2, wherein said elements are provided with a tapered flange.
6. In combination, a mandrel, a groove in said mandrel, voltage division means in said groove, a plurality of contact elements, means common to said contact elements and to said mandrel to lock said elements at any point of said groove in conductive engagement with said voltage division means and interpolating means connected to said contact elements.
7. In combination, a mandrel, a groove in said mandrel, a recess in said groove, first voltage division means in said groove, a plurality of contact elements, means to lock said contact elements by means of said undercut at any point of said groove in conductive engagement with said first division means, second voltage division means, wiping means adapted to be conductively disposed along the length of said second division

means and conductor means connecting selective points on said second division means to said contact elements.

8. The combination according to claim 7, wherein said second division means is circular in form and wherein the rotation of said wiping means is mechanically continuous.

9. The combination according to claim 8, wherein said conductor means include a plurality of studs connected to said contact elements 10 and a plurality of sliders connected to said selective points on said second divider and to said studs.

10. The combination according to claim 9, including displacing means to move said sliders between respective studs relative to displacement of said wiping means.

11. The combination according to claim 10 wherein said studs are arranged in a single, circular array.

12. The combination according to claim 11 wherein the operation of said displacing means is intermittent.

JERZY J. WILENTCHIK.
